(57) **CLAIM**

We claim the ornamental design for a powered appliance support strap, as shown and described.

DESCRIPTION

FIG. 1 is a front perspective view of a powered appliance support strap connected to an example shoulder strap; FIG. 2 is a front perspective view of the powered appliance support strap of FIG. 1;

FIG. 3 is a rear perspective view of the powered appliance support strap of FIG. 1.

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines represent portions of the structure that forms no part of the claim.
